UNITED STATES PATENT OFFICE.

MARTIN MOUL, OF HANOVER, PENNSYLVANIA.

SAFETY-GATE FOR ELEVATORS.

1,245,946.

Specification of Letters Patent. Patented Nov. 6, 1917.

Application filed August 21, 1917. Serial No. 187,339.

To all whom it may concern:

Be it known that I, MARTIN MOUL, a citizen of the United States, residing at Hanover, county of York, and State of Pennsylvania, have invented certain new and useful Improvements in Safety-Gates for Elevators, of which the following is a specification.

The object of my invention is the provision of an improved cage-controlled latching mechanism for holding open an automatically closing safety gate for freight elevators which requires opening by hand, thereby complying with laws or regulations which prohibit the use of an automatically opening gate and approve a self-closing gate which must be opened by hand and latched.

In carrying out my invention I provide a simple, reliable, and positively actuated latching mechanism which is operated by the cage when the latter is at the landing to so condition the parts that when the counterweighted gate is opened by hand, it will be latched and will remain in that condition until the cage leaves the landing, whereupon the latch will release the gate and the latter will then automatically close.

The improved mechanism constituting my invention comprises a latch for engaging and holding open of the gate, a rock-shaft cooperatively related thereto, a spring actuated pull rod for turning the rock-shaft, and a trip or shoe for operating the pull rod, the trip being adapted for engagement by a suitable part of the cage. The action of the mechanism is direct and positive and it is designed to operate indefinitely without danger of getting out of order.

In the accompanying drawings:

Fig. 1 is a front elevation of a portion of an elevator cage, landings, and adjacent parts, the self-closing gate being shown in dotted lines and my improvements in full lines;

Fig. 2 is a side elevation thereof with certain parts broken away and others in section; and

Fig. 3 is a detail perspective of the rock-shaft and oppositely set cranks.

It will be understood that the gate and my mechanism can be used at any landing and in connection with any elevator but it is illustrated with a freight elevator such as is commonly used in factories, warehouses, and the like.

Two of the floors or landings are shown

at 1, 2, the counterweight box for the cage appears at 3, the cage at 4, and one of the guides is shown at 5.

Dotted lines 6 represent a sliding gate 60 which is hung by any suitable sheave door hanger and is automatically closed by a counterweight 7. The gate 6 is intended to be opened by hand and slides laterally across the side of the elevator shaft. The 65 counterweight 7 keeps the gate normally closed.

Depending from the ceiling or the landing are hangers 8. A rock-shaft 9 is journaled in the hangers and carries oppositely 70 set cranks 10, 11. A gravity latch 12 which is pivoted to a suitable bracket 13, is adapted to drop over and engage a latch member 14 carried by the gate 6 when the gate is slid to open position as shown in Fig. 1. 75 The upper face of the member 14 and the face of the head of the latch are inclined or curved so that the latch will ride on the member 14 and then drop into locking engagement with it, when the gate is opened. 80 To permit this rise of the latch, it is provided with a slotted link 15 pivoted at 16 and receiving the pin 17 on the crank 10.

Pivoted at 18 to the counterweight box 3 is a trip or shoe 19 which is suitably 85 curved so that it will be properly engaged by the cage 4 when the latter is going either up or down. Anti-friction rollers 20 may be provided on the cage where it engages the trip. A pull rod 21 is engaged at its 90 upper end with the crank 11 at 22 and at its lower end with trip 19 at 23. A coil spring 24 surrounds the rod 21 between an adjustable set-collar 25 carried by the rod and a bracket 26 on the counterweight box 3. 95 The expansion of the spring 24 can be regulated by moving the collar 25 along the rod and fastening it in the desired position. The expansion of the spring positions the trip 19 where it will be engaged by the rollers 20 and also normally elevates the latch 12. Consequently, when the cage is above or below the landing, the gate 6 is free and is held in closed position by the action of the counterweight 7.

When the cage arrives at a landing, the trip 19 is pressed back, thereby elevating the rod 21, rocking the shaft 9 and lowering the latch 12 to a position where it will lock the gate open when the latter is opened by hand as shown in Fig. 1. The gate will remain in open, locked, position as long as the cage

stays at that landing. When the cage moves from the landing, the spring 24 swings the trip and also elevates the latch; consequently, the gate is released immediately the cage leaves the landing and the gate then automatically closes.

Having thus described my invention what I claim as new, and desire to secure by Letters Patent, is:—

10. The combination with a self-closing gate for an elevator, of a cage-controlled latching mechanism comprising a trip arranged to be engaged by the cage when the latter is at the landing, a rock-shaft, cranks carried thereby, a latch adapted to engage and

lock the gate when the latter is opened, a link having a pin and slot connection with one of the cranks, a pull rod connecting the remaining crank with the trip, a bracket, a collar on the pull rod, and a coil spring 20 surrounding the pull rod and interposed between the collar and the bracket, said spring keeping the trip normally in position for engagement by the cage and the latch normally out of position for engagement with 25 the gate.

In testimony whereof, I hereunto affix my signature.

MARTIN MOUL
